SIGURD L. WALSOE, OF SPRINGDALE, CONNECTICUT, ASSIGNOR TO REMINGTON TYPE-WRITER COMPANY, OF ILION, NEW YORK, A CORPORATION OF NEW YORK

TYPEWRITING MACHINE

Application filed September 19, 1928. Serial No. 393,786.

My invention relates to typewriting and like machines and more particularly to means for preventing a rebound of the carriage from its position of arrest by the tabulator mechanism.

The main object of my invention, generally stated, is to provide improved means of the character specified which are simple in construction, strong and not liable to be injured or broken in use and which are reliable and highly efficient in operation.

A further object of my invention is to provide means of the character specified which may be readily applied as an attachment to existing machines without modifying, or materially modifying, the existing structural features thereof.

A still further object of my invention is to provide means of the character referred to which are applicable to and may be efficiently employed in connection with tabulating mechanism including column stops located at letter space intervals and which are individually shiftable to and from operative position and in which a plurality of denominational stops are used for cooperation with said column stops.

To the above and other ends which will hereinafter appear my invention consists in the features of construction, arrangement of parts and combinations of devices set forth in the following description and particularly pointed out in the appended claims.

In the accompanying drawings, wherein like reference characters indicate corresponding parts in the different views;

Fig. 1 is a fragmentary, detail side elevation, with parts in section, disclosing a part of a typewriting machine equipped with the devices of my invention.

Fig. 2 is a fragmentary front elevation of the same, with parts broken away and in section.

Fig. 3 is an enlarged, detail, perspective view of the attachment including the devices of my invention, said attachment being shown removed from the machine.

Figs. 4, 5, 6 and 7 are enlarged, detail, perspective views of the different devices that go to make up the attachment of my invention.

My invention is in the nature of an improvement on the construction disclosed in the patent to George A. Seib No. 1,689,058 dated October 23, 1928.

The present invention is shown embodied in a No. 20 Remington typewriting machine, so much of the tabulating mechanism as is shown in the accompanying drawings being the same as that ordinarily employed in said machine. Such mechanism is as follows:

The frame of the machine comprises corner posts 1, a top plate 2 on which fixed guide rails are mounted, one of which is indicated at 3. The usual carriage 4 has front and rear guide rails, the latter being indicated at 5. Crossed anti-friction rollers 6 are interposed between the guide rails 3 and 5 and the corresponding guide rails (not shown) at the front of the carriage to support the latter in its travel from side-to-side of the machine over the top plate.

The carriage is impelled in the direction of its feed by the usual spring drum (not shown) under the control of the carriage escapement mechanism. The latter includes a feed rack 7 mounted on a frame 8 pivoted at 9 to the rear cross bar or rail 5 of the carriage. The teeth of the feed rack mesh with a feed pinion 10 operatively connected in the usual manner to an escapement wheel 11 which is controlled by the usual feed dogs, (not shown) to afford the step-by-step letter-space advance of the carriage at the actuation of the printing keys.

The tabulator mechanism proper is the same as that ordinarily employed in said machine and includes bracket arms 12 each secured at its forward end to the carriage and at its rear end to a column stop bar 13. This bar is provided substantially throughout its length with interdental spaces 14 separated at letter-space intervals and having in each of them a bifurcated sheet metal column stop 15 adapted to be shifted fore and aft of the machine from the inoperative full line position shown in Fig. 1, to the operative position shown in dotted lines in the same view. A spring detent 16 is attached to each column stop to limit its rearward movement and hold it against accidental displacement from

either of the positions to which it may be shifted.

A key set device is usually employed to effect an individual setting of each of the column stops that is to be shifted to operative or effective position, and a wiper is employed to clear such stops or shift them all forward to inoperative position. While these devices have not been shown in the present instance, 10 it should be understood that the embodiment of the devices of the present invention does not interfere with the employment of said key set and wiper devices.

The key controlled denominational stop mechanism which coacts with the column stops is shown in part only. Such mechanism comprises a tabulator frame 17 secured to the typewriter frame. Pivoted in the tabulator frame is a series of key actuated denominational stop levers 18, each controlled by a separate key. The upper forwardly extending free end of each of said levers constitutes a denominational stop 19. These stops are separated at letter space intervals 20 and each on the actuation of its key is projected into the path of those column stops which have been shifted to operative position.

In shifting any of the denominational stops to operative position a release of the carriage from control of its escapement mechanism is automatically effected thus enabling the carriage to travel until arrested by the projected denominational stop coacting 30 with the first approaching column stop. The carriage releasing mechanism in the present instance includes the usual means (not shown) by which an actuation of any denominational stop actuates a link 20 pivoted at 35 21 to a swinging frame 22 pivoted at 23 to a bracket 24 secured to the top plate of the machine. The frame 22 is provided with bearings for a shaft 25 that carries a rack lifting pinion 26 at one end thereof. The 40 opposite end of said shaft carries a carriage retarding device that rotates within a drum 27 connected to the frame 22. On an actuation of a denominational stop the frame 22 is turned on its pivots raising the pinion 26 and throwing it into mesh with the feed rack 7 and lifting said rack out of mesh with the feed pinion 10. The carriage being thus freed from its escapement mechanism and 45 will travel in the direction of its feed. The travel of the carriage at this time will rotate the shaft 25 and thus control the rate of speed at which the carriage travels.

When pressure on the key of the actuated denominational stop is released the pinion 26 50 will swing back to its normal position shown in Fig. 1, thus restoring the carriage to control of its escapement mechanism usually at the selected position determined by the tabulator mechanism. However, it sometimes occurs that the carriage in being arrested by

the tabulator mechanism will rebound from its intended position of arrest, especially when the carriage receives a long run before being arrested. It sometimes occurs that the operator will release the actuated tabulator key to permit the feed rack to re-engage the feed pinion 10 while this rebound is taking place. In this event the carriage will not be arrested in the position intended, and this fact not being observed by the operator an entry is effected in which the numerals will appear in the wrong denominational positions in the column of figures and the set-up in the adding mechanism, when one is employed, will be erroneous.

One of the objects of my invention is to overcome this difficulty and provide efficient and reliable means for preventing a rebound of the carriage from its positions of arrest by the tabulator mechanism, which means 80 will now be described.

The construction thus far described is the same as that employed in the No. 20 Remington machine and while the devices of my invention may be readily applied as an attachment to said machine, and may be employed in conjunction therewith, without modifying, or materially modifying its existing structure, it should be understood that the invention is not restricted to embodiment in such machines but may be employed in typewriting and like machines generally, wherever found available.

Ordinarily a bracket plate is employed in the machines referred to, which is connected to the top of the tabulator frame and has a downwardly and rearwardly bent end that stands just in front of the column stop bar to prevent the latter from being flexed forward when the column stop clearing wiper referred to above is acting on the column stops to clear them. Such bracket in the present instance is replaced by the sheet metal bracket 28, shown in detail in Fig. 4.

The bracket 28 has slots 29 that receive the shanks of headed screws 30 received at their threaded ends in tapped openings in the top of the tabulator frame 17. This provides a means for readily attaching the bracket together with the parts carried thereby to the machine as a single unit, and for affording a limited lateral adjustment of the bracket in order that the anti-rebound pawl or device carried by the bracket may properly coact with the column stops, as will presently appear. The bracket 28 has a depending arm 31 that terminates in a rearwardly extending end portion 32 to coact with the column stop bar for the same purpose as the arm usually employed and which has been hereinbefore referred to.

In addition the bracket carries an anti-rebound pawl or device 33 (shown in detail in Fig. 5), a holding device or controlling member 34 (shown in detail in Fig. 6) and a sec-

ond holding device or controlling member 35, shown in detail in Fig. 7. The bracket 28 is provided with bearings 36 to receive a fixed pivot 37 on which the pawl 33 is mounted between the arms 38 in which the bearings 36 are provided. To the left of the pivotal axis of the pawl 33, and in the top thereof, is a depression 39 in which the depending end of a wire spring 40 is seated to exert its force 10 against the pawl to lower the nose thereof into engagement with the upper edges of the column stops 15. The opposite end of the spring 40 is anchored to the bracket 28 by a headed screw 41.

15 The two holding devices 34 and 35 coact with the pawl 33 to normally maintain the engaging nose thereof out of cooperation with the column stops. I will first describe the holding device 34 and indicate how it is controlled and how it controls the pawl 33.

20 A pivot rod 42 is fixed at its ends in bearings 43 provided on the device 34, and said pivot rod receives a bearing in the bearing openings in ears 44 which extend up from the supporting bracket 28. A coiled spring 45 surrounds the pivot rod 42 and is anchored at one end to the bracket 28. The other end 46 of this spring bears against the front face of the member 34 and exerts its force rearward 25 against the latter. The force of the spring 45 is greater than the force of the spring 40 and is effective to overcome the latter and hold the pawl 33 against the power of the spring 40 in the elevated or ineffective position, as will 30 presently appear. The device 34 is provided with a forwardly projecting arm or finger 47 that overlies a tail or extension 48 on the pawl 33 and holds the engaging nose of the pawl elevated, it being remembered that the force 35 of the spring 45 is greater than that of the spring 40.

40 A cross bar 49 on the member 34 extends into the path of the upper ends of all of the denominational stops 19 to be actuated by the projecting of any of said stops 19 to effective position, without, however, interfering with the projecting of the actuated stop 19 into the path of the column stops 15. The positive movement of the member 34 against the force 45 of its returning spring 45 is effective to raise the arm 47 off the tail of the pawl 33 thereby relieving the pawl from the pressure of the spring 45. At this time the pawl 33 would be free to be moved by its spring 40 to effective 50 position were it not for the second holding device 35. However, the latter is effective to hold the pawl 33 in ineffective position, and continues to be effective for this purpose until the carriage has moved far enough to 55 bring the first advancing column stop into contact therewith and actuates it, as will now be described.

60 The second controlling or holding device or member 35 consists of a sheet metal part 65 formed as shown in detail in Fig. 7. De-

pending perforated ears 50 on the controlling device 35 receive a pivot rod 51 which in turn receive a bearing in openings in ears 52 on the bracket 28 and thus pivotally support the member 35 on the bracket. One of the side 70 arms of the member 35 is provided with an arm that terminates in a finger or projection 53 arranged parallel with the finger 47, and like the latter, overlying the tail 48 of the anti-rebound pawl. A contractile returning spring 54 is connected at one end to the member 35 and at the other end to the bracket 28 and tends to return said member to normal 75 position. The force of the spring 54 is greater than that of the spring 40 and therefore 80 will restrain the pawl 33 against movement to effective position when the member 35 is in normal position, in the same manner as the holding device 34. The member 35 has its two side arms united by a cross bar 55. The lower edge of this cross bar is formed as a cam comprising the oppositely inclined faces or edges 56 and an intermediate dwell 57. The extent of or length of this cam is slightly greater than the widthwise space occupied 85 by the series of denominational stops, as will be seen by an inspection of Fig. 2. This cam is situated in front of the denominational stops but out of the path thereof, and in a position where it will coact only with the 90 top edges of those column stops 15 which are set rearward to operative position, as will be understood from an inspection of the dotted line showing of the operative column stops disclosed in Fig. 1. The inoperative column 95 stops 15, shown in full lines in Fig. 1, are not effective on the cam 56, 57. It is only on the approach of the next advancing effective column stop 15 to the projected denominational stop 19 that such column stop will be 100 brought into contact with the cam 56, 57 and lift the member 35 from the full to the dotted line position shown in Fig. 2, the column stop which has effected the lifting of the member 35 being indicated at a. The 105 effect of thus elevating the member 35 is to carry the finger 53 thereon up from the projection 48 on the pawl 33, thus releasing the latter and enabling its spring 40 to lower the pawl to effective position where its nose will 110 engage one of the column stops 15 (either an effective or ineffective one) on the right hand side thereof and lock the carriage in and against rebound from the exact letter space 115 position where it is intended to be arrested by the coacting or engaged tabulator stops 15 and 19. It will be understood that the effect will be substantially the same whether a denominational stop of the highest or lowest order is actuated. In the latter case the holding device will release the pawl 33 and permit its spring 40 to force it to effective position at a slightly earlier period relative to the time of arrest by the tabulator stops than in the former case. However, in this event 120 125 130

the pawl will merely click over the advancing column stops until the arrest is effected, when the pawl will be in position to prevent rebound of the carriage from such position. 5 In both cases the pawl is not lowered to operative position until the advancing column stop to be arrested has almost reached the projected denominational stop.

From the foregoing it will be understood 10 that there are two factors that enter into consideration in effecting a release of the pawl or anti-rebound device 33 to enable its spring 40 to move it to operative position. One factor is the projection of a denominational stop 19 to operative position which results in moving the holding device 34 from normal position and releasing the effective force of its spring 45 on the pawl 33, the second holding 15 device 35 still maintaining the pawl in inoperative position. The second factor is the movement of the holding device 35 from normal position to release the effective force of the spring 54 from the pawl. This last mentioned operation is automatically brought about by the travel of the carriage, and by a 20 column stop causing the member 35 to be moved to the elevated position shown in dotted lines in Fig. 2. It will be understood therefore that unless both of these factors are involved the anti-rebound pawl 33 25 will not be rendered operative. This constitutes an important feature of the invention from certain aspects thereof, and valuable results are attained thereby as will now be pointed out.

Remington machines of the character referred to herein are sometimes equipped with automatic carriage return mechanism similar to that disclosed in the Hart Patent #1,663,374 dated March 20, 1928. It sometimes occurs that an operator will actuate a tabulator key after making the last entry, to complete the travel of the carriage to the end of the line and throw into operation the 30 electric motor and bring about a return of the carriage to the beginning of the line position. Now, in the event that the anti-rebound device or pawl is thrown into operation by this mere actuation of the tabulator key then the anti-rebound device is apt to be effective at the same time as the carriage return mechanism, one operating to return the carriage and the other operating to prevent its return movement. When this condition applies the pawl 33 is apt to be held 35 jammed against return to normal position even after the operator releases the actuated tabulator key. This would result in holding the carriage against return movement while the carriage return motor is attempting to return it, which might result in burning out and destroying the motor.

One of the main objects of my invention is to overcome this defect. It will be understood that a column stop 15 which could coact

with a denominational stop to arrest the carriage at the end of the line is never set in operative position to attain such a result. There would be no object at any time in setting such a column stop in operative position. It follows, therefore, in the present construction that when the carriage reaches the end of a line there will be no operative column stop to coact with the holding device 35 to elevate it. Consequently the anti-rebound device or pawl 33 cannot be released from its inoperative position at this time and permitted to function. Therefore, by the use of the present construction no injury to the motor can result from the causes pointed out. At all times when it is necessary to have the anti-rebound device operate it will function properly, but only at such times.

Aside from the advantages of the present construction hereinbefore pointed out, it will be understood that the devices readily lend themselves to use in connection with tabulator mechanism of the type disclosed, wherein closely arranged column stops and closely arranged denominational stops are employed, affording but little space for the use of anti-rebound devices carried by either set of such stops.

From certain aspects the stops 15 and 19 may be regarded as tabulator stops, from other aspects as column and denominational stops respectively and from still other aspects each of the stops 19 may be regarded as a key controlled counter stop and such terms are variously employed in the claims.

While I have described the invention in detail in one form or embodiment thereof it should be understood that various changes may be made in the construction, and some of its features may be employed without others, without departing from my invention as it is defined in the accompanying claims.

What I claim as new and desire to secure by Letters Patent is:

1. The combination of a carriage; tabulator mechanism including column stops and a key controlled counter stop; a normally ineffective anti-rebound device carried by the frame of the machine and cooperative with the column stops to prevent rebound of the carriage when the latter is arrested by said tabulator mechanism; and two independently operable controlling devices for affording a movement of said anti-rebound device to operative position, one of said controlling devices being controlled by the counter stop and the other by an effective column stop as it approaches the projected counter stop, the successive operations of both of said controlling devices being necessary to bring about a movement of said anti-rebound device to operative position.

2. The combination of a carriage; tabulator mechanism including column stops and a key controlled counter stop; a normally in-

effective anti-rebound device carried by the frame of the machine and cooperative with the column stops to prevent rebound of the carriage when the latter is arrested by said tabulator mechanism; and two independently operable controlling devices for affording a movement of said anti-rebound device to operative position, one of said controlling devices being in the path of movement of and controlled by the counter stop and the other of said controlling devices being in the path of and controlled by an effective column stop as it approaches the projected counter stop, the successive operations of both of said controlling devices being necessary to bring about a movement of said anti-rebound device to operative position.

3. The combination of a carriage; tabulator mechanism including column stops and a key controlled counter stop; a normally ineffective anti-rebound device carried by the frame of the machine and cooperative with the column stops to prevent rebound of the carriage when the latter is arrested by said tabulator mechanism; and two independently operable controlling devices for affording a movement of said anti-rebound device to operative position, one of said controlling devices being controlled by the counter stop and the other having a cam operated on by an effective column stop as it approaches the projected counter stop, said cam carrying controlling device being thus shifted to afford a movement of the anti-rebound device to operative position.

4. The combination of a carriage; tabulator mechanism including column stops and a key controlled counter stop; a normally ineffective anti-rebound device for preventing rebound of the carriage when the latter is arrested by said tabulator mechanism; a spring for moving said anti-rebound device to operative position; and controlling means for enabling said anti-rebound device to be moved to operative position, said controlling means including a cam acted on by a column stop as it approaches the actuated counter stop and effective to release said anti-rebound device and enable its spring to move it to operative position.

5. The combination of a carriage; tabulator mechanism including column stops and a key controlled counter stop; a normally ineffective anti-rebound device for preventing rebound of the carriage when the latter is arrested by said tabulator mechanism; a spring for moving said anti-rebound device to operative position; and controlling means for enabling said anti-rebound device to be moved to operative position, said controlling means including a cam acted on by a column stop as it approaches the actuated counter stop and effective to release said anti-rebound device and enable its spring to move it to operative position, and a holding device con-

trolled by an actuation of said key controlled stop for releasing said anti-rebound device, it requiring an actuation of both said cam and holding device to afford a movement of the anti-rebound device to operative position.

6. The combination of a carriage; tabulator mechanism including column stops and a key controlled counter stop; a normally ineffective anti-rebound device for preventing rebound of the carriage when the latter is arrested by said tabulator mechanism; a spring for moving said anti-rebound device to operative position; and a spring returned holding device coacting with the anti-rebound device and the force of the spring of which is sufficient to overcome the spring of said anti-rebound device and hold the latter in inoperative position, said holding device being positively acted on by a column stop in its approach to the projected counter stop and thereby effect a shifting of the holding device against the force of its spring to release the anti-rebound device.

7. The combination of a carriage; tabulator mechanism including column stops and a key controlled counter stop; a normally ineffective anti-rebound device for preventing rebound of the carriage when the latter is arrested by said tabulator mechanism; a spring for moving said anti-rebound device to operative position; a spring returned holding device coacting with the anti-rebound device and the force of the spring of which is sufficient to overcome the spring of said anti-rebound device and hold the latter in inoperative position, said holding device being positively acted on by a column stop in its approach to the projected counter stop and thereby effect a shifting of the holding device against the force of its spring to release the anti-rebound device; and a second spring returned holding device coacting with the anti-rebound device and the force of the spring of which overcomes the force of the spring of said anti-rebound device, said last mentioned holding device being shifted against the force of its spring by projecting the counter stop to effective position.

8. The combination of a carriage; tabulator mechanism including column stops and a key controlled counter stop; a normally ineffective anti-rebound device for preventing rebound of the carriage when the latter is arrested by said tabulator mechanism; and controlling means for enabling said anti-rebound device to be moved to operative position, said controlling means comprising two independently operable holding devices cooperative with said anti-rebound device, one of said holding devices being under control of said key actuated counter stop and the other being under control of a column stop in its approach to the projected counter stop, it requiring an actuation of both of said holding devices in order to bring about a move-

ment of the anti-rebound device to operative position.

9. The combination of a carriage; tabulator mechanism including column stops and a key controlled counter stop; a normally ineffective anti-rebound device for preventing rebound of the carriage when the latter is arrested by said tabulator mechanism; and controlling means for enabling said anti-rebound device to be moved to operative position, said controlling means comprising two independently operable holding devices cooperative with said anti-rebound device, one of said holding devices being under control of said key actuated counter stop and the other being under control of a column stop in its approach to the projected counter stop, it requiring an actuation of both of said holding devices in order to bring about a movement of the anti-rebound device to operative position, a spring for moving the anti-rebound device to operative position, and a spring of greater force for each of said holding devices for returning them to normal position and overcoming the force of the spring for the anti-rebound device.

10. The combination of a carriage; tabulator mechanism including column stops and a key controlled counter stop; a normally ineffective anti-rebound device for preventing rebound of the carriage when the latter is arrested by said tabulator mechanism; and controlling means for enabling said anti-rebound device to be moved to operative position, said controlling means comprising two independently operable and holding devices pivoted on the frame of the machine and coacting with said anti-rebound device, one of said holding devices extending into the path of the key actuated counter stop to be actuated thereby and the other holding device having a cam that is acted on by a column stop advancing to coact with the projected counter stop and thus effect an actuation of the associated holding device.

11. The combination of a carriage; tabulator mechanism including column stops and a key controlled counter stop; a normally ineffective anti-rebound device for preventing rebound of the carriage when the latter is arrested by said tabulator mechanism; and controlling means for enabling said anti-rebound device to be moved to operative position, said controlling means comprising two independently operable holding devices pivoted on the frame of the machine and coacting with said anti-rebound device, one of said holding devices extending into the path of the key actuated counter stop to be actuated thereby and the other holding device having a cam that is acted on by a column stop advancing to coact with the projected counter stop and thus effect an actuation of the associated holding device, a spring for moving said anti-rebound device to operative posi-

tion, and a stronger spring for returning each of said holding devices to normal position, thereby overcoming the force of the spring for the anti-rebound device and releasing the latter only by an actuation of both of said holding devices as specified.

12. The combination of a carriage; tabulator mechanism including a series of column stops and a series of key controlled denominational stops; a normally ineffective anti-rebound device cooperative with said column stops to prevent rebound of the carriage when the latter is arrested by said tabulator mechanism; and means for rendering said anti-rebound device effective comprising a holding member coacting with said anti-rebound device for holding it in ineffective position, and a cam carried by said holding member and of an extent slightly greater in length than the width of the series of denominational stops and with which a column stop advancing to the position of arrest by a projected denominational stop coacts to move said holding member and thereby release the anti-rebound device.

13. The combination of a carriage; tabulator mechanism including a series of column stops and a series of key controlled denominational stops; a normally ineffective anti-rebound device cooperative with said column stops to prevent rebound of the carriage when the latter is arrested by said tabulator mechanism; and means for rendering said anti-rebound device effective comprising a holding member coacting with said anti-rebound device for holding it in ineffective position, a cam carried by said holding member and of an extent that is slightly greater in length than width of the series of denominational stops and with which a column stop advancing to the position of arrest by a projected denominational stop coacts to move said holding member and thereby release the anti-rebound device, and a second holding member coacting with said anti-rebound device to hold it in ineffective position and having a portion thereof that is in the path of all of said denominational stops to be actuated by an operation of any of them and when actuated release the anti-rebound device, an actuation of both holding members being required to afford a movement of said anti-rebound device to effective position.

14. The combination of a carriage; tabulator mechanism including a series of column stops and a series of key controlled denominational stops; a normally ineffective anti-rebound device cooperative with said column stops to prevent rebound of the carriage when the latter is arrested by said tabulator mechanism; and means for rendering said anti-rebound device effective comprising a holding member coacting with said anti-rebound device for holding it in ineffective position, a cam carried by said holding member and of

an extent that is slightly greater in length than the width of the series of denominational stops and with which a column stop advancing to the position of arrest by a projected denominational stop coacts to move said holding member and thereby release the anti-rebound device, a second holding member coacting with said anti-rebound device to hold it in ineffective position and having a portion thereof that is in the path of all of said denominational stops to be actuated by an operation of any of them and when actuated release the anti-rebound device, an actuation of both holding members being required to afford a movement of said anti-rebound device to effective position, a spring for moving said anti-rebound device to effective position, and a spring of greater force for each of said holding members for returning them to normal position and overcoming the force of the spring for the anti-rebound device.

15. The combination of a carriage; tabulator mechanism including a series of column stops mounted on the carriage at letter space intervals for adjustment to and from operative position and a series of key controlled denominational stops; an anti-rebound pawl carried by the frame of the machine and cooperative with said column stops to prevent a rebound of the carriage when it is arrested by said tabulator mechanism; and means for controlling the movement of said anti-rebound pawl into and out of cooperative relation with said column stops, said controlling means including a cam-carrying holding member cooperative with said pawl, the cam on said holding member being acted on only by those column stops which are adjusted to operative position in order to afford a movement of said pawl to operative position.

16. The combination of a carriage; tabulator mechanism including a series of column stops mounted on the carriage at letter space intervals for adjustment to and from operative position and a series of key controlled denominational stops; an anti-rebound pawl carried by the frame of the machine and cooperative with said column stops to prevent a rebound of the carriage when it is arrested by said tabulator mechanism; and means for controlling the movement of said anti-rebound pawl into and out of cooperative relation with said column stops, said controlling means including a cam-carrying holding member cooperative with said pawl, the cam on said holding member being acted on only by those column stops which are adjusted to operative position in order to afford a movement of said pawl to operative position, a spring which tends to move said anti-rebound pawl to operative position, a returning spring of greater force for each of said holding members and each of which in returning its holding member to normal position moves the pawl to inoperative position against the force of its spring.

17. The combination of a carriage; tabulator mechanism including a series of column stops mounted on the carriage at letter space intervals for adjustment to and from operative position and a series of key controlled denominational stops; an anti-rebound pawl carried by the frame of the machine and cooperative with said column stops to prevent a rebound of the carriage when it is arrested by said tabulator mechanism; and means for controlling the movement of said anti-rebound pawl into and out of cooperative relation with said column stops, said controlling means including a cam-carrying holding member cooperative with said pawl, the cam on said holding member being acted on only by those column stops which are adjusted to operative position in order to afford a movement of said pawl to operative position, and a second holding member cooperative with said pawl and controlled in its movement by the movement into and out of effective position of any one of said denominational stops, it requiring the actuation of both of said holding members to afford a movement of said pawl to operative position.

18. The combination of a carriage; tabulator mechanism including a series of column stops mounted on the carriage at letter space intervals for adjustment to and from operative position and a series of key controlled denominational stops; an anti-rebound pawl carried by the frame of the machine and cooperative with said column stops to prevent a rebound of the carriage when it is arrested by said tabulator mechanism; and means for controlling the movement of said anti-rebound pawl into and out of cooperative relation with said column stops, said controlling means including a cam-carrying holding member cooperative with said pawl, the cam on said holding member being acted on only by those column stops which are adjusted to operative position in order to afford a movement of said pawl to operative position, a second holding member cooperative with said pawl and controlled in its movement by the movement into and out of effective position of any one of said denominational stops, it requiring the actuation of both of said holding members to afford a movement of said pawl to operative position, a returning spring of greater force for each of said holding members and each of which in returning its holding member to normal position moves the pawl to inoperative position against the force of its spring.

Signed at Stamford, in the county of Fairfield and State of Connecticut, this 18th day of September A. D. 1929.

SIGURD L. WALSOE.
